UNITED STATES PATENT OFFICE.

WILLIAM H. HART, JR., DECEASED, LATE OF PHILADELPHIA, PENNSYLVANIA; BY
WILLIAM B. HART, EXECUTOR, OF PHILADELPHIA, PENNSYLVANIA.

NECKWEAR CLIP.

Application filed October 25, 1923. Serial No. 670,660.

To all whom it may concern:

Be it known that WILLIAM H. HART, Jr., deceased, a citizen of the United States, residing in the city and county of Philadelphia, State of Pennsylvania, has invented a new and useful Neckwear Clip, of which the following is a specification.

This invention relates to a clip for an article of neckwear more particularly of the order of a bow tie, and it consists in forming the clip of opposite resilient members adapted to be connected with the tie and easily fitted to and conveniently adjusted on a collar, said members being axially mounted on a joint piece which permits freedom of articulation or flexibility of the members independently of each other, thus permitting flexibility of the tie whereby it may be set on the collar with the best effects of appearance.

It consists also of details of construction as will be hereinafter set forth.

The invention is satisfactorily illustrated in the accompanying drawing, but the important instrumentalities thereof may be varied, and so it is to be understood that the invention is not limited to the specific details shown and described as long as they are within the spirit or scope of the claims.

Figure 1 represents a rear elevation of a neckwear clip embodying the invention, showing it also in position on an article of neckwear.

Figure 2 represents a perspective view of the clip.

Figure 3 represents an elevation of the joint member of the clip in normal condition removed from the remainder of the clip.

Figure 4 represents a transverse section of the joint member on line 4—4 Figure 2.

Figure 5 represents a longitudinal section of the device on line 5—5 Figure 2.

Figure 6 represents a rear elevation of another embodiment of the invention.

Figure 7 represents a horizontal section thereof on line 7—7 Figure 6.

Figure 8 represents an elevation of the embodiment shown in Figure 6.

Figure 9 represents a longitudinal section of another embodiment of the invention.

Figure 10 represents a rear elevation of another embodiment of the invention.

Figure 11 represents a top or plan view thereof.

Figure 12 represents a front elevation thereof.

Figure 13 represents a longitudinal section thereof, on line 13—13 Figure 12.

Similar numerals of reference indicate corresponding parts in the figures.

Referring to the drawings.

1 designates a clip for a bow tie the same consisting of opposite members 2 separated from each other and connected centrally by 65 the joint piece 3.

Each member is formed of a piece of resilient metal or other suitable material which is bent on itself and comprising the limb 4 which is adapted to be stitched, sewed or otherwise connected with the back of the tie, and the limb 5 which latter is somewhat set-out from said limb 4 at the outer ends thereof and flaring at its terminals to provide well defined inlets between the limbs so as 75 to permit said limbs to receive between them the edge portions of the front of a collar when applied thereto, and so clasp said portions whereby the members are held frictionally in position on the collar. 80

The central joint piece 3 consists of a plate of metal or other suitable material which is bent on itself in somewhat flat tubular form and has on the sides of its inner walls the loops or ears 6 on which the bends 85 7 of the members 2 are mounted, thus connecting said members and allowing the latter to be articulatively movable on said loops as a fulcrum whereby the members are movable on the loops to and from the bow, 90 and they may be manipulated by hand so as to be presented to the aforesaid opposite end portions of the collar and pushed thereover when the limbs 4 and 5 embrace or clasp said portions as above stated, and so the tie 95 will be held on the collar in wearing position.

In order to prevent the opposite members 2 of the clip from moving towards each other, there is employed the guard 8 which 100 is formed of a sheet of pliable metal or other material and placed in part behind the central wall 9 of the joint piece 6 and has its side ends 10 flaring or salient outwardly so as to overhang the bends 7 of the opposite 105 members 2, and thus prevent inwardly sliding motions of said members. Then the upper and lower portions 11 of the sheet are bent or wrapped over the back of the guard 8 and brought together forming a tube 110

whereby the guard is clasped and so held in position with the flaring or salient ends 10 in front of the bends 7 of the clip members 2 which ends while not preventing the articulation of said members control them from displacement from the loops or eyes 6.

In Figures 6, 7 and 8, the joint piece is formed of the double T-headed plate 11. The bent portions of the clip members 2 are 10 provided with longitudinally extending slots 12 in which the heads 13 of said plate are fitted so that the bends 7 of said members are mounted on said heads so as to be capable of articulation thereon, and the members 15 are prevented from moving towards each other and displacement.

In Figure 9 the joint piece is tubular and the front wall 14 thereof is thrown out forming a guard whose ends while preventing disengagement of the members 2 from the eyes or loop 6 permit said members to articulate on said eyes or loop, as in the previous instances.

In Figures 10, 11, 12 and 13, the outer 25 ends of the inner limbs 4 of the members 2 are connected by rivets 15 with the outer ends of the resilient or flexible bar 16 on the backs of said members, said bar being continuous from one member to the other 30 and the central portion 17 thereof which is intermediate of the bends 7 of said members forms the joint piece of the members, thus retaining the latter separated from each other to receive the edge portions of the 35 front of the collar, as in the previous case.

The rivets 15 are hollow or tubular whereby stitches may be passed through to sew the members to the tie. In order to prevent the members from turning on the bar 16 40 and vice versa, and so becoming displaced, there are applied to the limbs 4 and said bar adjacent to the bends 7 of the members, the clips 18 which are adapted to clasp the contiguous parts and so interlock them the effect of which is evident.

As the bar 17 is resilient or flexible, the clips, and the members 2 may be readily ma-

nipulated to present them to the collar and adjust them thereon and permit the clip to be adjusted on the tie to the best advantage. 50

Having thus described the invention of WILLIAM H. HART, Jr., deceased, what is claimed as new and desired to secure by Letters Patent, is:—

1. A neckwear clip consisting of separate 55 opposite resilient members formed of limbs adapted to receive between them the front edge portions of a collar and frictionally embrace the same, a central joint piece having thereon eyes on which said members are 60 each articulatively mounted and means upon said joint piece adapted to control said members from motion towards each other and displacement from their operative positions.

2. A neckwear clip consisting of separate 65 opposite resilient members formed of limbs adapted to receive between them the front edge portions of a collar and frictionally embrace the same, a central joint piece having thereon eyes on which said members are 70 each articulatively mounted, and a guard on said joint piece adapted to control said members from motion towards each other and displacement from their operative positions. 75

3. A neckwear clip consisting of separate 80 opposite resilient members formed of limbs adapted to receive between them the front edge portions of a collar and frictionally embrace the same, a central point piece having thereon eyes on which said members are each articulatively mounted, a guard on said joint piece adapted to control said members from motion towards each other and displacement from their operative positions, 85 and means on said joint piece for retaining said guard thereon.

WILLIAM B. HART,
*Executor of the Estate of William H. Hart,
Jr., deceased.*
